(57) **CLAIM**

The ornamental design for a log splitting device, as shown and described.

DESCRIPTION

FIG. 1 is a front perspective view of a log splitting device;
FIG. 2 is a front elevational view thereof;
FIG. 3 is a right elevation view thereof;
FIG. 4 is a top plan view thereof;
FIG. 5 is a rear elevation view thereof;
FIG. 6 is a left elevation view thereof; and,
FIG. 7 is a bottom plan view thereof.
The broken lines showing environment are for illustrative purposes only and form no part of the claimed design.
